UNITED STATES PATENT OFFICE.

WILLIAM H. WILLIAMS, OF NEW YORK, N. Y.

VENEER-SLICING MACHINE.

SPECIFICATION forming part of Letters Patent No. 651,287, dated June 5, 1900.

Application filed February 10, 1900. Serial No. 4,792. (No model.)

To all whom it may concern:

Be it known that I, WILLIAM H. WILLIAMS, a citizen of the United States, residing at New York city, (Long Island City,) Queens borough, in the county of Queens and State of New York, have invented new and useful Improvements in Veneer-Slicing Machines, of which the following is a specification.

By means of this invention an automatic setback can be obtained for causing the knife or knife-bed to recede and permit the log when returning to escape contact with the knife or cutter and then causing the knife to resume its position ready for cutting.

15 The invention is set forth in the following specification and claims, and illustrated in the annexed drawings, in which—

Figure 1 is a face elevation of a veneer-slicing machine. Fig. 2 shows parts in a different position than in Fig. 1. Fig. 3 is an end elevation of Fig. 1. Fig. 4 shows a driving mechanism. Fig. 5 is a plan view of setting-screws. Fig. 6 is a longitudinal sectional view of shoes. Fig. 7 is a transverse view of Fig. 6.

The stay-log *a* is reciprocated to carry the log to or past the cutter or blade *b* to slice off a layer or veneer and then return to again start drawing the log over or past the knife.

30 The stay-log moves in its support or along guides or ways *c* and connects by links *d* with arms or cranks *e* on shafts *f*. The shafts *f* have arms *g*, connected by links *h*, so that the parts *d* move in unison with one another.

35 The shafts *f* (or one of them) are oscillated or rocked by suitable means, as a crank and link *e**, connected to an arm *e* or *g*. As this feature is known no detail description thereof is required.

40 The knife *b* is mounted on holder *h*, carried by bed *i*, resting on plate *k*, which can be leveled or adjusted up or down by screws *m* and rests on shoes (or rather supplemental shoes) *n*, carried by lower or main shoes *o*.

45 Each of shoes *o* is engaged by a screw or threaded rod *p*, Fig. 5, and these rods connect by miter-gears with a shaft *q*, extended across the machine and having a setting-wheel *r*. By turning wheel *r* and shaft *q* one

50 way or another the screws *p*, which are threaded right and left hand, respectively, cause the shoes *o*, with knife-holder and knife

b, to be set toward or from stay-log *a*, as required.

The supplemental shoes *n*, Figs. 6 and 7, 55 are mounted to slide on ways or tracks on shoes *o*, and these supplemental shoes can be set or moved on the main shoes by screws *s*, Fig. 5, which are also threaded right and left hand, respectively, and are connected to 60 one another by miter-gears and shaft 1.

One of the screws or rods *s* is extended, as seen at *s*', Fig. 5, and has a feather connection with a pinion or gear *2*, which can rotate but not move laterally. This pinion *2* is engaged 65 by segmental gear *3*, Figs. 1 and 3, on lever *4*, fulcrumed at *5*. A swivel *6* has its gudgeons supported in lever *4*, and through this swivel passes a sliding rod *7*, pivoted or connected to one of the arms *g*. The slide *7* has collars 70 or nuts *8*, Figs. 1 and 2, which can be set suitably apart, so that such collars will only strike or move lever *4* as the slide *7* arrives near the end of its respective strokes or oscillations. The slide coming near the end of its 75 stroke in one direction, a collar *8* will strike and move lever *4*, with screws *s*, so as to move shoes *n*, with knife *b*, away from stay-log *a* sufficiently for the knife to be out of contact with or out of the path of the log. The latter can now make its return stroke without 80 touching the knife.

As the stay-log arrives at its upper or starting point the other collar *8* strikes or shifts lever *4* sufficiently to cause a slight rotation 85 of gear *1*, with screws *s*, whereby shoes *n* are moved toward the stay-log sufficiently to bring knife *b* into the path of the log. As the latter now makes its down or cutting stroke the log is drawn over the knife-edge, 90 so that slicing is effected.

What I claim as new, and desire to secure by Letters Patent, is—

1. A reciprocating stay-log, and its support, combined with a cutter or knife, two sets of 95 shoes for supporting the knife, and screw mechanism connected with the two sets of shoes for setting and feeding the same, so as to cause the knife to recede for permitting the log on its return to escape contact with the knife and then causing the knife to move to cutting position, substantially as described.

2. A stay-log, and its support, combined with a cutter or knife, main and supplemental

shoes for supporting the knife, the feed-screws *p*, the shaft *q* geared with said feed-screws and provided with a setting-wheel *r*, the rocking screws *s s'*, and a shaft 1 geared with and connecting said rocking screws, substantially as described.

3. A stay-log, and its support, combined with a cutter or knife, main and supplemental shoes for supporting the knife, and screw mechanism for connecting and operating the two sets of shoes for moving the knife, substantially as described.

4. A stay-log and its support, combined with a cutter or knife, a set of shoes on which the knife is mounted, another set of shoes on which the first-named shoes are adjustably mounted, and screw mechanism for connecting and operating the two sets of shoes to set and feed the said shoes, substantially as described.

5. A stay-log and its support combined with a cutter or knife, main and supplemental shoes for the knife, set-screws for the main shoes, and screws for adjustably connecting the main and supplemental shoes substantially as described.

6. A stay-log and its support, combined with a cutter or knife, a set of shoes for supporting the knife, another set of shoes on which the first-named shoes are adjustably mounted, two sets of oppositely-located screws for setting and feeding the said shoes, and cross-shafts and miter-gears for connecting said screws, substantially as described.

35. 7. A stay-log and its support, combined with a knife or cutter, main and supplemental shoes for supporting the knife, oppositely-located screws *s s'* for the supplemental shoes, the cross-shaft 1 connected with said screws by miter-gears, a gear or pinion 2 on one of said screws, a segmental gear 3 and an arm 4 for actuating said pinion, feed-screws *p* for the main shoes, and a shaft *q* geared with and connecting said feed-screws, substantially as described.

45. 8. A stay-log and its support, and a mechanism, substantially as described, for actuating the said log, combined with a shaft hav-

ing a pinion 2 actuated by said mechanism, main and supplemental shoes, setting-screws 50 engaged with said supplemental shoes, one of said screws being feathered in said pinion, feed-screws engaged with the main shoes, a shaft geared with and connecting said feed-screws, and a cutter or knife supported upon 55 the supplemental shoes, substantially as described.

9. A stay-log and its support and an arm for oscillating the stay-log, combined with a segmental gear and a pinion rocked by said 60 arm, a screw *s* feathered in the pinion, a shoe moved back and forth by the screw, and a knife carried by the shoe substantially as described.

10. A knife-supporting shoe and a screw 65 and pinion for said shoe combined with a gear-arm for the pinion, a swivel or sleeve 6 trunnioned in the gear-arm, a slide-rod 7 having stops or collars 8 to engage the swivel, a stay-log, and an actuator for the stay-log and slide- 70 rod substantially as described.

11. A stay-log and its support and arms for actuating the stay-log, combined with a slide-rod actuated by one of the arms, a segmental gear having an arm in which the slide-rod 75 moves and which is actuated by the slide-rod, a pinion actuated by the segmental gear, a screw actuated by the pinion, a shoe engaged by the screw and a knife carried by the shoe substantially as described.

12. A stay-log and actuating-arms for the stay-log, combined with rock-shafts for the arms, arms *g* linked to one another and made to actuate the rock-shafts, a slide-rod 7 jointed to one of the arms *g*, a segmental gear actuated by the slide-rod, a pinion and screw actuated by the gear, and a knife-supporting shoe engaged by the screw substantially as 85 described.

In testimony whereof I have hereunto set 90 my hand in the presence of two subscribing witnesses.

WILLIAM H. WILLIAMS.
